UNITED STATES PATENT OFFICE.

STANLEY W. HAYES, OF RICHMOND, INDIANA, ASSIGNOR TO HAYES TRACK APPLICATION COMPANY, OF RICHMOND, INDIANA, A CORPORATION OF INDIANA.

PORTABLE DERAIL.

Application filed July 25, 1925. Serial No. 45,968.

The invention relates to a quick releasable light portable derail suited to a wide range of rail sections, having an adjustable road-bed-contacting thrust-receiving member dividing the vertical wheel thrust with the derail block, a quick applicable and quick-releasable adjustable clamping jaw and other distinctive features pointed out in the following specification or made apparent to those skilled in the art. These structural characteristics though novel and of value individually are advantageously combined in the preferred form of invention shown in the accompanying drawings, in which—

15 Fig. 1 is a side elevation of the derail in released position;

Fig. 2 is a side elevation showing clamping jaw in the position to which it has been shifted manually and in readiness for the 20 short power movement which completes the clamping.

Fig. 3 is a side elevation showing the derail in clamped position; and

Fig. 4 is a view corresponding to Fig. 3 25 showing the derail clamped to a larger rail, parts of most of these figures being broken away and other parts sectioned to show internal structure.

Fig. 5 is a top plan of the applied derail.

30 Fig. 6 is an underside plan.

Fig. 7 is a detail cross section on the line VII—VII, Fig. 5 through the clamping jaw, adjusting screw bolt and adjacent parts.

35 Fig. 8 is a detail plan showing the slot and countersink in the top of the derail body, and

Fig. 9, an end elevation of the clamping jaw looking away from the rail.

40 Rapidity and ease of application and release are a primary characteristic of this derail. When once adjusted for a given rail section, it may be applied thereto or released therefrom, as will be hereinafter explained in detail, mainly by a single rapid manual movement which is supplemented by bringing power applying means very briefly into play to merely finish the clamping movement or begin the release movement, the application of power being reduced to the minimum. As portable derails must often be removed and replaced—

and always where speed and ease of application and release are desirable, this characteristic is of vital importance.

The derail has a bearing on the top of the rail, a bearing on the road bed and a bearing on the underside of the head of the rail adjustable up against the underside of the rail head and thereby exerting downward pressure on both of the other bearings and clamping the derail on the rail. The derail illustrated has the derailing member consisting of the body 1 and derail block 2 having usual wheel-derailing contours made as one casting recessed on the underside for lightness and to provide room for and to protect moving parts, and an adjustable thrust-receiving road-bed-abutting member, the screw bolt 3, passing down through the body and adjustable in the fixed removable nut 4 thus dividing the vertical wheel thrust with the derail block and providing for vertical adjustment to suit rails 75 of heights both greater and less than those shown. The tail of the body may itself rest on the tie where the rail is low enough. The derail block has in its underside a rail-head-receiving recess which sets down onto the rail head but is wider than the rail head to suit rails of different cross section. The depending flange 5 on the derail block forms the outer wall of this recess between which and the clamping jaw 6 the rail head is 85 clamped. This jaw is mounted in the underside of the body of the derailing member at one side of the recess for quick manual movement under or out from under the rail head and for camming by a brief application 90 of power up against the underside of the rail head into clamping position by movement relative to inclined cam surface on the derail body as will be hereinafter explained. The clamping jaw in the illustrated derail 95 is a floating jaw being loosely mounted so as to be capable of movement in various directions, and in this embodiment of the invention it is also a lever having turning movement around its fulcrum whose position 100 changes. For greater effectiveness in clamping the jaw 6 is constructed with two distinct camming and clamping members spaced apart lengthwise of the rail but integrally united by the jaw body which is 105 designed by longitudinal, transverse and up-

right connecting walls to afford a structure braced against the considerable strains to which it is subjected, and capable of housing certain of the parts and whose end walls 5 7, 8 lie in planes transverse of the rail and by outwardly projecting flanges, provide two upwardly facing correspondingly curved tracks 9, 10, shown as rockers curved lengthwise on the arc of a circle and having their 10 rear and front ends suitably rounded as indicated respectively at 11, 12, for sliding contact of the portions 11 with upward and railward cam inclines, the ribs 13, 14, and for resultant clamping contact of the portions 15 12 with the rail. To avoid useless and annoying projections and for convenient support when not assembled the jaw 6 has the bottoms of its end walls flat and in the same horizontal plane below the rest of the 20 jaw. The jaw is releasably and adjustably supported in the body 2 by the supporting, adjusting and clamping screw bolt 15 passing downward and railward through the elongated slot 16, whose railward end is 25 rounded by a countersink 17 cooperating with the bevel 18 of the head 19 of the bolt 15 to form bearing means supporting the bolt when at the railward end of the slot, as it is in the clamping operation, and to 30 preclude possibility of derail release by pushing the bolt with the rest of the movable clamping structure backward when in clamped position. The bearings afford the bolt considerable freedom of movement in 35 other directions thus promoting flexibility and ready self-accommodation of the parts to each other and to the rail in clamping and in releasing which is one of the especially desirable characteristics of this derail. Below said slot the bolt passes freely 40 through a hole in the top or raised part of the jaw body midway between its end walls and is screw-threaded through the nut 20 carried loosely in the jaw body so that relative movement between it and the jaw 45 readily occurs, thus further promoting the flexibility referred to. It is held against rotation by upright walls 21, 22, 23 of the jaw body which forms a rectangular recess 50 open at its railward end for insertion and removal of the nut, under which lie the flange lugs 24, 25 which receive the thrust of the nut while the screw bolt 15 is turned reversely in releasing and which project toward each other from the parallel walls 21, 23. A cotter pin 26 in the end of the screw bolt 15 prevents the nut and the jaw from falling off the bolt under any circumstances. Between the nut and the underside of the 55 jaw body is a split spring washer 27 providing a lost motion connection to permit backing off of the screw bolt 15 after clamping for purposes hereinafter explained. It will be observed that in the illustrated de- 60 rail the axis of the adjusting screw bolt 65

intersects the plane of the cam-inclines, extending downward and railward whereas the said plane extends upward and railward. The endwise or railward movement of the clamping jaw is thus doubly insured. The 70 hole midway of the end walls of the jaw-body through which the bolt 15 passes has its center in rear of the central transverse plane of the jaw. Spaced a little behind the hole and the screw bolt therein is an up-standing abutment 6' which furnishes leverage enabling the bolt 15 which acts against it in the rearward movement to release the clamping jaw when stuck to the body of the derail. The projection 6' is bevelled at 80 each end lengthwise of the rail and it and adjacent parts of the raised top of the body of the jaw extend back into the space between the cam-inclines when the parts are in the released position. Further means of 85 support for the jaw and parts connected therewith effective when the jaw is screwed well down on the bolts 15 is provided in the lugs 28, 29, projecting inward, i. e. toward each other from the end walls 7, 8 90 of the jaw body and on which the undersides 30, 31 of the jaw body flanges may at times rest.

As indicated in Fig. 1, which shows the derail between the rails adjusted to suit the rail section, the adjustable thrust-receiving bolt 3 also acts at full release as a support for the jaw-adjusting screw bolt 15 and connected parts, the head 19 of the latter being in contact with the eye 3' of the former, both ends of the clamping jaw being then free, though the parts of the tracks 9, 10 near the far end of the jaw may rest against the adjacent cam inclines. The derail having been so far applied as shown in this figure all that remains to be done to clamp it to the rail is to pull or shove the bolt 15 with associated parts upward and forward to its bearing in the countersink 17, which may be done by a single quick manual movement, the principal shift of the jaw being thus accomplished the tracks 9, 10 being moved along the corresponding cam inclines 13, 14, and to complete the clamping by giving the bolt 15 a few turns, which may readily be done by means of handle 32, whose spaced end lugs embrace the flattened head end of the bolt to which it is swivelled at 33. This turning of the bolt 15 exerts a pulling or drawing effect on the clamping jaw and carries the front end of the jaw up into final clamping position under the rail head, the rear parts of the jaw which abut on and are movable with respect to the inclines assisting in this operation. In this 115 position the tracks 9, 10 by their front ends 12 and adjacent surfaces, at the same time contact both the web and the underside of the ball of the rail, the loose mounting of the jaw permitting it to accommodate itself 130

to these rail surfaces. By virtue of the duplicate camming and clamping members, this action occurs at two points spaced well apart along the rail. The clamping action is thus firm and positive and precludes sliding. The spring washer 27 preserves the clamping effect and admits of backing off the screw bolt 15 so as to register the slot 32' of its handle with the eye 3' of the adjustable thrust-receiving bolt 3 and permit it to pass over the eye and be locked in clamped position by padlock 34 passed through the eye and which may be chained to the tie. But the padlock is not required 10 to maintain the jaw clamped. Quick derail release is effected by reversing the mode of derail applying and clamping above described. A few reverse turns of the screw bolt 15 provide sufficient play to enable the bolt with attached parts to be pulled up and thrust back, the bevel 18 of the bolt clearing the countersink, which is done by a single manual upward and backward pull or jerk, the parts once the countersink has been 15 cleared falling downward and backward by gravity or assisting this movement by their weight. At the heel of the derail block slot 35 designed to receive a banner staff passes through the hand hold 36. Guides 37 extend down at each end of the slot.

The range of adjustment, division of vertical wheel thrust, efficiency of the clamping, speed of application and release with minimum power movement, capability of backing off in clamped position without impairing effectiveness of the clamping, facility of locking, and the securing of all these advantages in a small light derail are meritorious and novel features characteristic of this invention.

Claims:

1. A portable derail capable of quick application and release comprising a derailing member having a unitary derail block provided with wheel-derailing contours and having also rail clamping structure movably mounted on and beneath said derailing member at one side of the rail and including power applying means for merely finishing the clamping movement and beginning the release movement, and means for manually effecting the quick rough application and release of the rail clamping means by shifting said clamping structure toward 45 and from the rail.

2. A portable derail capable of quick application and release comprising a derailing member having a unitary derail block provided with wheel-derailing contours, a clamping jaw movably mounted on the derailing member for cooperation with the underside of the rail head, means for shifting said jaw a relatively long distance by manual movement from released position in which 50 the derail is free to be removed from the rail,

to a position closely adjacent rail clamping position, or from the latter to the former, and power applying means operatively connected to the jaw to move it through a relatively short distance to merely finish rail clamping or effect jaw release for the manual shift.

3. A portable derail capable of quick application and release, having a derailing member and in addition thereto a clamping jaw movably mounted on the derailing member beneath its derailing portion for movement under the rail head to clamp or release the rail, means for shifting said jaw by a single manual movement from released position to a position closely adjacent rail clamping position or from the latter to the former, and power applying means for finishing the rail clamping movement or releasing the jaw for the manual shift.

4. A portable derail capable of quick application and release comprising a derailing member having a derail block provided with wheel-derailing contours, a clamping jaw extending crosswise of the rail and mounted on the derailing member for endwise movement with respect thereto under the rail head toward and from the rail, means for rapidly shifting the jaw railward by a manual movement for rough application of the jaw, and power applying means carried by the derailing member for moving the clamping jaw transversely into clamping contact with the rail head to finish the clamping.

5. A portable derail having a derailing member having a bearing on the road bed, a floating clamping jaw supported from said derailing member, a screw bolt screw-threaded into said jaw, coating supporting bearings on said member and bolt and a slot adjacent the same extending away from the rail, whereby the jaw may be shifted by a quick manual movement from released position to a position closely adjacent rail clamping position and whereby a quick jaw release is provided by rearward and downward movement of said jaw and connected parts after freeing the bolt from its support in the body of the derailing member.

6. A portable derail having a derailing member having a bearing on the roadbed and provided with a derail block having wheel-derailing contours and having in its top a keyhole slot extending from its enlarged end away from the rail, a rail-clamping jaw movably supported under the derail body, a screw bolt having a bearing at the keyhole end of the slot and extending down through the slot into screw threaded connection with the clamping jaw, whereby said bolt may be manually shifted lengthwise of the slot to quickly effect rough application and release of the jaw, said jaw on release of the clamping bolt from its supporting bearing being adapted to be dropped down

and back to released position, said screw bolt constituting power means for completing the clamping and initiating the release of the jaw, and stop means for said dropping parts.

7. A portable derail having a derailing member provided with a derail block and with a body having a bearing on the roadbed, a clamping jaw extending crosswise of the rail, a screw bolt adjustably connected to said clamping jaw, and passing through a slot in the derail body, a forward and a rearward support for said screw bolt, whereby the screw bolt when released from its forward support may, gravity aiding, be thrown along with the jaw downward and rearward to its rearward support.

8. A portable derail having a derailing block provided with wheel-derailing contours and adapted to set down onto a rail head, a clamping jaw mounted on the derail and having rail engaging surface, and adjustable means for clamping said jaw against the rail, said means including a spring which at clamping position urges the rail engaging surface against the rail and thereby permits the adjusting means to be backed off somewhat without releasing the rail clamping action.

9. A portable derail having a screw bolt extending down through said derail and screw-threaded through a stationary nut therein, a rail clamping jaw carried by said screw bolt, and a spring washer interposed between said nut and jaw and at clamping position urging said jaw toward that position and thereby permitting the screw bolt to be backed off somewhat without releasing the clamping action.

10. A portable derail having a derailing member having a bearing on the top of the rail, a bearing on the roadbed, and a bearing on the underside of the rail head, and means mounted on the derailing member for forcing the last bearing up and the other two down to clamp the derail on the rail.

11. A portable derail having a derailing member having a bearing on the top of the rail, and an adjustable bearing on the roadbed, a jaw movably mounted on the derailing member and adjustable means for forcing it up against the underside of the head of the rail and thereby exerting downward pressure on both said bearings.

12. A portable derail having a derailing member provided with an adjustable rail-clamping jaw adapted to be forced against the underside of the rail head, and an adjustable roadbed-contacting wheel-thrust-receiving member mounted in the derailing member at one side of the track.

13. A portable derail having a derailing member provided with a derail block adapted to set down on to the rail and with a thrust transmitting member bearing on the

roadbed, and rail clamping means mounted on said derailing member between them and adapted to act on the near side of the rail.

14. A portable derail adapted to extend transversely away from the rail at one side thereof and having a body provided at one end with a derail block having in its underside a recess adapted to set down over the rail head and at the other end with a roadbed abutment, and in a recess in the underside of said body between its ends with a clamping jaw extending crosswise of the rail, and means for camming the clamping jaw into rail clamping position.

15. A portable derail having a derailing member provided at its front end with a derail block having a flange cooperating with the far side of the rail head and at its rear with an adjustable bearing on the roadbed, a floating clamping jaw loosely mounted in the derailing member and means carried by the derail for clamping the jaw against the near side of the rail.

16. A portable derail having a derailing member provided with a derail block and with a roadbed abutment, a rail clamping jaw mounted in a recess in the underside of said derailing member between them, a screw bolt having a bearing for rotation in the derailing member, passing through the same into said recess and having screw-threaded operative connection with said clamping jaw, and a cam incline on which said jaw may be caused to ride by rotation of said bolt to clamp the derail to the rail.

17. A portable derail having a derail block provided with wheel-derailing contours and a body having a bearing on the roadbed, a clamping jaw mounted on said body and having a rail-head-bead contact portion and a rail-web contact portion below the rail head, and adjustable means for moving said contact portions upward and railward against the bead and web respectively to clamp the derail on the rail.

18. A portable derail having a derail block provided with wheel-derailing contours and a body having a bearing on the roadbed, a clamping jaw loosely mounted in a recess in the underside of said body and having a rail-head-bead contact portion and a rail-web contact portion below the rail head, and means for camming said contact portions upward and railward against the bead and web respectively to clamp the derail on the rail.

19. A portable derail having a wheel-derailing block and having in its underside a recess adapted to set down over rail heads of various cross section, a screw-bolt constituting a road bed abutment adjustable in the body of the derail, a clamping jaw mounted in the derail and having rail engaging surface, an adjusting screw bolt screw-threaded into said jaw for moving it

into clamping relation to the rail, the adjusting screw bolt having a slotted handle, and a spring acting on the clamping jaw in clamping position to urge it against the rail thereby permitting the adjusting bolt to be eased off without impairing the rail clamping action, the roadbed abutment screw bolt having an eye with which the slot of the handle may be brought into registration to enable the clamped derail to be locked on the rail.

20. A portable derail having a derail block adapted to set down onto the rail and a body extending transversely away from the rail at one side thereof and having at a distance from the rail an adjustable road bed abutment bolt passing through said body, a rail-clamping jaw movably mounted in the derail body, a bolt passing down through said body and screw-threaded into said jaw for adjusting the same with respect to said body and to the rail to clamp the derail on the rail on the side toward the road bed abutment and means for thereafter locking said bolts against relative rotation.

21. A portable derail comprising a derailing member having a derail block provided with wheel-derailing contours and having a depending flange for contact with one side of the rail head, and adjacent said flange a rail-head-receiving recess wider than the rail head, a clamping jaw extending crosswise of the rail, mounted on the derailing member on the other side of the rail and having its rail-clamping portion below the rail head, and adjustable means for moving said rail clamping portion upward and railward toward said depending flange and against the underside of the rail head to clamp the derail onto the rail.

22. A portable derail carrying loosely mounted thereon a floating rail-clamping jaw and having cam incline surface on which the jaw abuts, a screw bolt having supporting bearing means on the derail and operatively connected to the jaw for moving the jaw along the cam incline surface and thereby camming it against the rail to clamp the derail thereon.

23. A portable derail having a body having a bearing on the roadbed and a derail block adapted to set down onto rail heads of different cross section and having an upward and railward cam incline on the underside of the body of the derail, a rail-clamping jaw having a portion adapted to contact with said cam-incline, and a clamping bolt mounted in bearings in the derail

body and having screw-threaded connection with the clamping jaw, the axis of the bolt intersecting the plane of the cam incline.

24. A portable derail having a derail block, and a body having a bearing on the road bed, a clamping jaw having a cam contact portion and a rail contact portion and carrying loosely in its body a nut held against rotation, a screw bolt mounted for rotation in bearings in the derail body and extending down freely through a hole in the jaw body and screw threaded through said nut, and a fixed cam surface on the derail body, with which the cam contact portion of the clamping jaw cooperates when the screw bolt is turned, whereby the rail contact portion is cammed against the rail to clamp the derail thereon.

25. A portable derail having a derail block provided with wheel-derailing contours and two sets of camming and rail clamping means located in a recess in the underside of the derail and means for operating both sets at once to cam the movable members of both sets against the rail at points spaced lengthwise thereof to clamp the derail to the rail.

26. A portable derail having a rail-head receiving recess of variable size to suit rails of different cross section and a bearing on the road bed, a floating jaw having abutment surfaces spaced lengthwise of the rail for camming contact respectively with correspondingly spaced surfaces on the underside of the body of the derailing member inclined upward and railward, and rail-head-contact surfaces spaced lengthwise of the rail, and means for supporting the floating jaw from the derail adjustably.

27. A portable derail having a derailing member having a derail block and a body having a bearing on the roadbed and in the underside of the body a recess and railward cam inclines abutting thereon and spaced apart lengthwise of the rail, a clamping jaw having at the end distant from the rail correspondingly spaced abutting surfaces adapted to slide on the cam inclines and at its railward end rail-abutting clamping surface, a screw bolt supported in the body of the derail, extending down through a slot in said body extending crosswise of the rail and having screw-threaded connection with the jaw, and additional jaw supporting means on the body of the derail.

In testimony whereof, I have signed this specification.

STANLEY W. HAYES.
